UNITED STATES PATENT OFFICE.

JOHN W. HYATT, OF NEWARK, NEW JERSEY.

DISINTEGRATING-MACHINE.

SPECIFICATION forming part of Letters Patent No. 423,870, dated March 18, 1890.

Application filed December 3, 1889. Serial No. 332,378. (No model.)

To all whom it may concern.

Be it known that I, JOHN W. HYATT, a citizen of the United States, and a resident of Newark, in the State of New Jersey, have invented certain new and useful Improvements in Disintegrating-Machines, of which the following is a specification.

These improvements relate to the class of disintegrating-machines in which the shredding operation is performed by a system of so-called "drunken saws," consisting of a series of circular saws mounted upon a common shaft in planes which are parallel with each other, but which diagonally intersect the shaft upon which the saws are mounted.

The invention embraces certain feeding, guiding, and stripping devices, and the combination of said devices, respectively, with a system of drunken saws in a machine for disintegrating sugar-cane and other woody or vegetable material.

The accompanying drawings of a machine containing the invention are as follows: Figure 1 is a top view, partly in section. Fig. 2 is a rear elevation. Fig. 3 is an end elevation. Fig. 4 is a front elevation of the rotating feeder, showing its strippers and some of the adjacent portions of the machine. Figs. 5 and 6 are respectively an elevation and a top view of the guiding-blades for attachment to the feed-table. Figs. 7 and 8 are respectively a view of the edge and of the face of one of the stripping-plates for the rotating feeder. Figs. 9 and 10 are respectively a side elevation and a top view of one of the laterally-vibrating supporting-fingers. Fig. 11 is a transverse vertical section of the machine, taken through the plane indicated by the dotted line $x-x$ on Fig. 1. Fig. 12 is a top view of the drunken saws, illustrating a modification of the supporting and stripping fingers, which consists in making them in one piece with or rigidly affixing them to an end-wise-movable bar.

The machine represented in the drawings embraces a saw-shaft A, provided with suitable bearings $a-a$ in the frame B, and with a driving-pulley A' for the reception of the belt by which the saw-shaft is rotated. The saw-shaft A carries a system of drunken saws, which, as heretofore ordinarily constructed,

is composed of a series of circular saws C, equidistantly mounted upon the saw-shaft in planes which are parallel to each other, but which diagonally intersect the shaft. The 55 saws are separated from each other by means of interposed washers or disks, and are clamped together between collars affixed to the shaft in the usual manner.

The sugar-cane or other material to be disintegrated, which is hereinafter called simply the "cane," is deposited upon the delivery-belt D, by which it is carried to and delivered upon the table D' in position to be caught by the rotating feeder E, and fed forward forcibly 65 against the saws. The rotating feeder which it is preferred to employ in itself constitutes one part of the present invention. It is composed of a series of star-pointed wheels made of sheet metal, which are loosely mounted and 70 keyed upon the horizontal shaft E', provided with bearings E² in the frame of the machine and rotated by means of the sprocket-wheel E³, to which the sprocket-chain E⁴ is applied. One of the said star-pointed wheels 75 e is shown in detail in Fig. 11. It has a hole through it and an inwardly-projecting tongue e', which, when the star-wheel is slid on the shaft E', projects into the groove e², formed longitudinally in the surface of the shaft E'. The tongue e' is loosely contained within the 80 said groove e², and thus permits the star-wheel to slide longitudinally upon the shaft E', but serves as a key which compels the star-wheel e to partake of the rotatory motion 85 of the shaft E'. The star-wheels are kept equidistantly separated from each other by means of the system F of the stripping-plates f, which are rigidly secured to the horizontal girder F', bolted at its opposite ends 90 to the frame of the machine. This construction permits the star-wheels to be readily assembled upon the shaft which drives them, and, in case one of them should break, greatly increases the ease with which the broken 95 star-wheel can be removed and another one slipped on the shaft. It will be seen, therefore, that the plates f have an important relation to the structure by reason of the double function which they perform of strippers and of spacers for keeping the loose star-wheels in their proper relative positions. 100

The stripping-plates extend downward from the girder F' into the spaces between the star-wheels, respectively, and partially embrace the shaft E'. Each of them is preferably provided at its lower end with the downwardly-projecting blade f', having its sharp under edge downwardly inclined toward the saws, as shown in detail in Figs. 7 and 8.

The top of the table D' is preferably in the plane of the axis of the saw-shaft A. At the side of the table D' toward the saws it is provided on the top with a series of vertical guiding-blades d, the sharp upper edges of which incline downwardly and outwardly from the saws. The vertical planes of these guiding-blades are parallel with the planes of the star-wheels and perpendicular to the axis of the saw-shaft A. The inner edge of the table D' is at a sufficient distance from the saws to afford clearance for them; but in order to afford a support for the material which is being disintegrated, which shall extend beyond the inner edge of the feed-table, there is provided a system of laterally-movable stripping-fingers h, which project, respectively, into the spaces between the saws, and act not only as strippers for the saws, but as supporting-fingers, which detain the short pieces or butt-ends of the cane and prevent them from falling down into and clogging the spaces between the saws. The supporting-fingers may be rigidly attached to a horizontal bar II, as is represented in Fig. 12, to which endwise-reciprocating motion is imparted by the wabbling action of the saws upon the fingers and upon the shoulders II' and II'', which respectively bear upon the outer sides of the outermost saws. It is preferred, however, to make the stripping and supporting fingers h independently movable, which is conveniently effected by pivotally connecting their outer ends h' with the top of the horizontal girder I, which is arranged beneath the table D', and bolted at its opposite ends, respectively, to the end standards b b' of the machine. The inner portions of the fingers h are provided with the upward offsets h², the upper edges of which are substantially on a line with the surface of the table D'. It will be seen that it is the offset portion of each of the fingers h which projects into the space between the saws, and these portions are provided upon their opposite sides with the rounded bosses h³ h³ for bearing against the sides of the saws, respectively.

The saws are preferably protected at the top by the hinged shield A². A separate driving-shaft L is preferably employed for driving all the moving parts of the machine, except the saws, and is itself rotated by a belt applied to the pulley L'. The driving-shaft L is provided with a sprocket-wheel E⁵ for engaging the sprocket-chain E⁴, which drives the rotating feeder E, and is also provided with a sprocket-wheel d' for driving the sprocket-chain d², which engages the sprocket-wheel d³, affixed to the counter-shaft d⁴, from

which motion is imparted to the delivery-belt D by the engagement of the spur-wheel d⁵ with the pinion d⁶, affixed to the shaft of the driving-roller d⁷ of the delivery-belt D, which is an endless belt stretched over the driving-roller d⁷ and the stretching-roller d⁸. Motion is also taken from the driving-shaft L, by means of the miter-gears l l', to rotate the driving-roller N of the discharging-apron n, stretched across beneath the saws over the driving-roller N and the stretching-roller N'.

As will be seen, the saws operate to make a wide cut, owing to their diagonal positions with relation to their axis of rotation.

In operation the cane, forcibly fed against the drunken saws by the rotating feeder, is prevented from yielding laterally to the wabbling action of the saws by the vertical yielding blades d, which, in addition to affording lateral support for the cane, serve to guide it in paths perpendicular to the axis of the saws.

The laterally-movable stripping-fingers h may of course be arranged in a different part of the machine—as, for example, on the side of the drunken saws opposite that where the cane is delivered. They would in such case perform their stripping functions with equal effect; but by placing them in the position shown those portions of them which project into the spaces between the saws constitute extensions of the supporting-table and perform the additional function of supporting any short pieces of cane which may collect in the spaces between the saws, and of detaining such pieces in position where they will be subjected to more or less abrading action by collisions with the sides of the saw-teeth. The shredded cane falls from the saws upon the discharging-apron n, by which it is discharged at the side of the machine, where convenient access can be had to it.

It will of course be understood that if the machine is in an elevated position the discharging-apron n can be dispensed with and its place taken by a hopper placed beneath the saws for catching the shredded cane and guiding it into a chute for conducting it to a bin or any other receptacle which may be provided for it.

What is claimed as the invention is—

1. The combination, in a disintegrating-machine, as herein set forth, of a system of drunken saws with a system of stripping-fingers respectively projecting into the spaces between the saws, and having the capacity of vibrating laterally in a plane parallel with the axis of the saws.

2. In combination with a system of drunken saws, a system of independently-movable stripping-fingers composed of a series of fingers, each pivoted at one end and having its free end projecting into the space between two adjacent saws, substantially as shown and described.

3. A system of drunken saws, a table arranged in proximity thereto, and a rotating

feeder for feeding the material to be disintegrated across the said table to the saws, in combination with a system of laterally-movable supporting and stripping fingers arranged beneath said table but at one end, 5 extending beyond the same and into the spaces between the saws, as and for the purposes set forth.

4. In a disintegrating-machine, the combination, as herein described, of a system of drunken saws, a system of stripping-fingers projecting slightly into the spaces between the saws, respectively, and having the capacity of vibratory movement in a plane parallel 10 with the axis of the saws, a feed-table arranged in proximity to said saws, a system of parallel vertical blades affixed to and projecting upward from said table in planes perpendicular to the axis of the saws, and a rotating feeder above the said table, as and for 15 the purposes set forth.

5. In a disintegrating-machine, the combination, as herein described, of a system of drunken saws, a system of stripping-fingers 20 projecting slightly into the spaces between the saws, respectively, and having the capacity 25

of vibrating in a plane parallel with the axis of the saws, a feed-table arranged in proximity to said saws, and a rotating feeder arranged above the said table, as and for the 30 purposes set forth.

6. In a rotating feeder, the combination, as herein set forth, of the series of star-pointed wheels *e*, loosely keyed upon the shaft *E'* of said feeder, and the series of stationary 35 plates *f*, projecting into the spaces between the said star-pointed wheels for acting as strippers and for holding said star-pointed wheels at proper distances apart upon the shaft *E'*. 40

7. In a disintegrating-machine, the combination, as herein set forth, of the delivery-belt *D*, the table *D'*, the laterally-movable stripping and supporting fingers *h*, the shaft *A*, the system of drunken saws mounted 45 thereon, and the rotating feeder *E*, as and for the purposes described.
